UNITED STATES PATENT OFFICE.

MARVIN W. MORRISON, OF SCOTTSVILLE, KENTUCKY.

DEVICE FOR RAISING BUCKETS FROM WELLS.

1,250,619.

Specification of Letters Patent.

Patented Dec. 18, 1917.

Application filed January 27, 1917. Serial No. 144,870.

To all whom it may concern:

Be it known that I, MARVIN W. MORRISON, a citizen of the United States, residing at Scottsville, in the county of Allen and State of Kentucky, have invented certain new and useful Improvements in Devices for Raising Buckets from Wells; and I do hereby declare the following to be a full, clear, and exact description of the invention, such as 10 will enable others skilled in the art to which it appertains to make and use the same.

This invention relates to a device for raising buckets from wells and has for one of its objects the provision of a device of this 15 character especially adapted to be used in connection with bored or drilled wells for the purpose of removing buckets or other foreign obstacles therefrom.

Another object of this invention is to provide a frusto-conical shaped body having an 20 inwardly curved lower end for allowing the body to slide down freely within the well and having means therein adapted to grip a bucket or foreign obstacle, so that the same 25 will be withdrawn with the body.

A further object of this invention is to provide gripping arms pivoted within the body and having their ends so curved that they will coöperate with each other to form a 30 substantial circle whereby a bucket or foreign obstacle will be partially encircled thereby, thus tightly and efficiently gripping the bucket or foreign obstacle.

A still further object of this invention is 35 to provide a device for raising buckets from wells of the above stated character, which will be simple, durable and efficient, and which may be manufactured and sold at a comparatively low cost.

With these and other objects in view, which will become more apparent as the 40 description proceeds, the invention consists in certain novel features of construction, combination and arrangement of parts as 45 will be hereinafter more fully described and claimed.

For a complete understanding of my invention, reference will be had to the following description and accompanying drawings, in which:

Figure 1 is a vertical sectional view of a device for raising buckets from wells constructed in accordance with my invention, and

Fig. 2 is a sectional view taken on line 55 2-2 of Fig. 1.

Referring in detail to the drawing, the numeral 1 indicates a substantially frusto-conical shaped body having its lower end curved inwardly as illustrated at 2 for the purpose of allowing the body 1 to slide freely down within a well without being caught by the wall thereof. A substantially V-shaped rod 3 has its arm portion extending within the upper end of the body and 60 is riveted or otherwise secured thereto as illustrated at 4. The apex portion of the V-shaped rod 3 is bent to form a ring 5 for the purpose of receiving a chain or cable for lowering and raising the body 1 in a 70 well. A pair of oppositely disposed and substantially L-shaped brackets 6 are bolted or otherwise secured within the body 1 adjacent the curved lower end 2 and the free arm portions thereof are twisted as illustrated at 7 to dispose of the remaining portion of said arm portions in another plane. The free arm portions are provided with a plurality of apertures 8 for adjustably and pivotally securing gripping arms 9 thereto that 80 extend downwardly and are curved as illustrated at 10 to extend upwardly within the body 1. The free ends of the gripping arms 9 are bent to form arcuate shaped members 11, for the purpose of partially surrounding the bucket or other foreign obstacle within the well so that the bucket or 85 foreign obstacle will be withdrawn from the well upon withdrawing the body therefrom. Angularly related arms 12 are formed 90 upon the pivoted ends of the gripping arms 9 for balancing the same upon their pivots within the body so as to properly position said gripping arms whereby they will readily 95 grip the bucket or foreign obstacle within the well.

From the foregoing description taken in connection with the accompanying drawings, it will be noted that a device has been provided which will readily and efficiently 100 grip an obstacle within the well so that the same may be readily withdrawn therefrom. The conical shaped body provides means whereby the obstacle within the well will be guided into an engagement with the 105 hook so that said hook will readily grip the same when desiring to remove a bucket or other foreign obstacle from the well; the

device is lowered downwardly in the well by attaching a cable to the portion 5. The curved portions 10 of the arms 9 first engage the bucket or foreign obstacle, which causes the hooks 11 to move apart and engage about the bucket or obstacle, and by pulling upwardly upon the cable, the balancing arms 12 cause the hooks 11 to tightly clamp the same.

10 While I have shown and described the preferred embodiment of my invention, it will be understood that minor changes in construction, combination and arrangement of parts may be made without departing from 15 the spirit and scope of the invention as claimed.

Having thus described my invention, what I claim is:

20 1. A device of the character set forth comprising a frusto-conical body having its lower end curved inwardly, means for attaching a cable to said body, arms pivoted within said body and depending downwardly,

said arms being bent to extend upwardly in the body and having their free ends bent 25 in arcuate formation to grip a bucket.

2. A device of the character set forth comprising a frusto-conical shaped body having its lower end curved inwardly, means for attaching a cable to said body, substantially 30 L-shaped brackets secured within the body, arms adjustably and pivotally secured to the brackets and depending downwardly therefrom, and said arms being bent to extend upwardly and having their free ends 35 bent in arcuate formation and extending in opposite directions to grip a bucket, and weighted arms secured to the pivoted ends of the gripping arms to balance said arms.

In testimony whereof I affix my signature in presence of two witnesses.

MARVIN W. MORRISON.
